UNITED STATES PATENT OFFICE.

HENRY A. OWEN, OF WHITINSVILLE, MASSACHUSETTS, ASSIGNOR TO THE WHITIN MACHINE WORKS, INCORPORATED, OF SAME PLACE.

TRAVERSE-MOTION FOR SPINNING-MACHINES.

SPECIFICATION forming part of Letters Patent No. 637,019, dated November 14, 1899.

Application filed May 18, 1899. Serial No. 717,297. (No model.)

To all whom it may concern:

Be it known that I, HENRY A. OWEN, of Whitinsville, in the county of Worcester and State of Massachusetts, have invented a new and useful Improvement in Traverse-Motions for Spinning-Machines; and I hereby declare that the following is a full, clear, and exact description of the same, reference being had to the accompanying drawings, forming part 10 of this specification.

In spinning-machines the roving in its passage from the spools to the drawing-rolls is controlled by a trumpet mounted on a rod to which reciprocating motion is imparted, 15 whereby the roving is guided in its passage through the drawing-rolls to continuously change the points of contact of the roving with the drawing-rolls and top rolls to utilize as much of the drawing-rolls and top rolls as 20 possible, so as to prolong their life. This reciprocating motion has usually been imparted to the traverse-rod by means of a heart-shaped cam driven from one end of the spinning-machine. In traverse-motions of this construction 25 the wear on the top rolls and drawing-rolls, while it was distributed over a greater length of the rolls, caused the rolls to wear at the extreme ends, as the traverse always stopped at the same place, and the dwell 30 caused by the natural reverse motion made this wear more at these places.

The object of this invention is to impart an ever-changing reciprocation to the traverse-rod and prevent the dwell of the reciprocation 35 at the extreme ends of the traverse and the consequent greater wear of the rolls, particularly the top rolls, at the ends of the reciprocation.

The invention consists in the peculiar and 40 novel construction of the traverse-motion whereby the reciprocation of the traverse-rods and the trumpet, and thereby the path of the roving through the drawing-rolls, is continuously changed and the ordinary defect of the dwell of the traverse at the extreme 45 end of the throw of the cam is corrected.

Figure 1 is a transverse sectional view showing the drawing-rolls and top rolls and the mechanism for reciprocating the roving traverse-rod operated from the back drawing-roll. 50 Fig. 2 is a side view of my improved traverse-

motion. Fig. 3 is a sectional view on the line A A of Fig. 2. Fig. 4 is a sectional view on the line B B of Fig. 2. Fig. 5 is a diagram illustrating the path of the roving controlled by the reciprocation of the trumpets on the traverse-rod. 55

Similar letters of reference indicate corresponding parts in all the figures.

In the drawings, A A indicate the drawing-rolls; A', the back roll; B B, the top rolls; C, the traverse-rod, and C' C' the trumpets on the traverse-rod; A², a worm on the back roll A'; A³, a bracket secured to the front beam or other convenient stationary part of 60 the spinning-machine; A⁴, a slotted arm extending upward from the bracket A³, and A⁵ another slotted arm extending vertically from the bracket A³. The arms A⁴ and A⁵ are preferably made integral with the bracket A³. 70 In the slot of the arm A⁴ the stud D is adjustably secured, and on this stud is pivotally supported a bell-crank lever, the arm D' of which forms the support of the stud D², on which the worm-wheel D³ and the cam D⁴ are 75 journaled, as is shown in Fig. 3. The stud D may be adjusted in the slot of the arm A⁴, so as to bring the worm-wheel in proper mesh with the worm A² on the back roll A'. The frame D⁵ is secured to the traverse-rod C and 80 is provided with the pins D⁶ D⁶ on the opposite sides of the cam D⁴. The distance between the two pins D⁶ D⁶ and the shape of the cam D⁴ are designed to insure contact of the cam with the pins during the whole of 85 the revolution of the cam. The frame D⁵ is preferably provided with the slot D⁷, through which the end of the stud D² extends. A spring-pin may be inserted in the end of the stud D², as is shown in Figs. 1 and 2. The 90 arm D⁸ of the bell-crank lever supports the stud D⁹, on which the gear D¹⁰ is journaled. The gear D¹⁰ meshes with the worm-wheel D³ and is provided with either a greater or less number of teeth than the worm-wheel D³. 95 The gear D¹⁰ is provided on its outer side with the eccentric-disk D¹¹, which extends into the upper end of the arm D¹², the lower end of said arm being secured in the slotted arm A⁵ of the bracket A³. 100

When my improved traverse-motion is secured to a spinning-machine, the worm on the

back roll imparts rotary motion to the worm-wheel D^3 and to the cam D^4 . The cam, acting on the pins $D^6 D^6$, imparts reciprocating motion to the traverse roving-rod and the trumpet-
5 ets. The worm-wheel D^3 transmits its motion to the gear D^{10} , and the eccentric D^{11} , rotating within the arm D^{12} , pivotally secured at its lower end to the slotted arm A^5 of the bracket A^3 , imparts a rocking motion to the 10 bell-crank lever forming the supports for the worm-wheel D^3 , the cam D^4 on one arm and the gear D^{10} on the other arm, whereby at each revolution of the gear D^{10} the bell-crank lever, the gears, and the cam supported by the 15 bell-crank lever are made to oscillate.

In the drawings the gear D^{10} is shown provided with one more tooth than the worm-wheel D^3 . If the number of teeth in these two gears were equal, the oscillation of the 20 bell-crank lever, the cam, and the gears would continue to be equal. As, however, the number of teeth in the gear D^{10} is designed to be either greater or less than the number of the teeth in the worm-wheel D^3 , the oscillation of 25 the bell-crank lever and the cam is continually changing in its extent and the path of the roving controlled by the trumpets $C' C'$ continually changed in its traverse and its passage through the drawing-rolls.

30 In the diagram shown in Fig. 5 the lines E E indicate the normal traverse of one of the trumpets on the roving-rod produced by the rotation of the cam, and the lines F F indicate the extreme limit of the traverse of one 35 of the trumpets produced by the oscillation of the bell-crank lever and the cam carried by the same, the difference between the lines E E and F F being the traverse produced by the eccentric D^{11} in excess over that of the 40 cam D^4 .

In my improved stop-motion we have, first, the reciprocation incident to the action of the cam on the frame secured to the roving-rod; second, the oscillation of the bell-crank 45 lever caused by the eccentric D^{11} , and, third, the variations of this reciprocation caused by the difference in the number of the teeth of the gear D^{10} and the worm-wheel D^3 , whereby the roving controlled by the trumpets is made

to pass between the drawing-rolls and top 50 rolls to continually-changing points, and the wear on the drawing-rolls and top rolls is reduced to a minimum.

Having thus described my invention, I claim as new and desire to secure by Letters 55 Patent—

1. In a traverse-motion for spinning-ma- 60 chines, the combination with the back roll, a worm on the back roll, the traverse-rod and a frame secured to the traverse-rod, of a worm-wheel 65 engaging with the worm on the back roll, a cam connected with and rotating with the worm-wheel, projections on the frame secured to the traverse-rod acting on the cam, and a bell-crank lever one arm of which sup- 65 ports the journal-bearing of the worm-wheel and cam, the other arm supporting the journal, of a gear in mesh with the worm-wheel, an eccentric on the gear connected with the worm-wheel and an arm surrounding the ec- 70 centric and connected with a fixed part of the machine; whereby reciprocating motion is imparted to the traverse-rod by the cam and oscillating motion to the cam, as described.

2. In a traverse-motion for spinning-ma- 75 chines, the combination with the back roll, a worm on the back roll, the traverse-rod and the frame secured to the traverse-rod adapted to be operated by a cam, of the bracket A^3 , the slotted arms A^4 and A^5 on the bracket, a 80 bell-crank lever supported on the arm A^4 , the worm-wheel D^3 and cam D^4 supported on the arm D' of the bell-crank lever, the gear D^{10} , the eccentric D^{11} projecting from the gear D^{10} , and the arm D^{12} inclosing the eccentric D^{11} , the 85 lower end of the arm D^{12} secured to the arm A^5 of the bracket; whereby the normal reciproca- 90 tion imparted by the cam D^4 is increased by the changing position of the rotating eccentric D^{11} , as described.

In witness whereof I have hereunto set my hand.

HENRY A. OWEN.
